UNITED STATES PATENT OFFICE.

FRED B. McFEELY, OF LATROBE, PENNSYLVANIA, ASSIGNOR TO CONEMAUGH IRON WORKS, OF LATROBE, PENNSYLVANIA, A CORPORATION OF PENNSYLVANIA.

DESIGN FOR A LAVATORY.

Application filed March 18, 1927. Serial No. 21,194. Term of patent 14 years.

To all whom it may concern:

Be it known that I, FRED B. McFEELY, a resident of Latrobe, Pennsylvania, and a citizen of the United States, have invented a new, original, and ornamental Design for Lavatories, of which the following is a specification, reference being had to the accompanying drawings, forming a part thereof.

The figure is a perspective view of a lavatory showing my new design.

I claim:

The ornamental design for a lavatory as shown.

In testimony whereof I hereunto affix my signature.

FRED B. McFEELY.
